INVENTOR
Mitchell J. Lubow
BY Percy Freeman
ATTORNEY

UNITED STATES PATENT OFFICE.

MITCHELL J. LUBOW, OF NEW YORK, N. Y.

ELECTRIC-FIXTURE CANOPY.

Application filed January 6, 1922. Serial No. 527,343.

To all whom it may concern:

Be it known that I, MITCHELL J. LUBOW, a citizen of the United States, and resident of 367 West 118th Street, New York, in the county of New York and State of New York, have invented certain new and useful Improvements in Electric-Fixture Canopies, of which the following is a specification.

One of the purposes of this invention is 10 to provide an ornamental electrical fitting comprising a canopy, adapted to be fixed on a ceiling or wall, and means therewith for directly engaging the body of a commercial plug socket, in place of the usual cap 15 which is wholly dispensed with.

Another object is in the provision of a 20 novel joint between the canopy and socket, which provide for quick engagement or detachment by hand and also for axial adjustment, the joint at all times, when engaged being exceptionally strong, rigid and secure.

These aims are secured by the novel design, construction and disposition of parts 25 hereinafter described and shown in the accompanying drawing, forming a material part of this disclosure, and in which:—

Figure 1 is a side elevational view showing an embodiment of the invention applied 30 in a pendant position.

Figure 2 is a plan view of the same looking from the base or attaching end.

Figure 3 is a fractional sectional view of 35 the lower portion of the upper or fixed part of the device, drawn to an enlarged scale.

Figure 4 is a fragmentary sectional view showing the joint construction, the view being further enlarged.

In the drawing, a hollow metallic canopy 40 or casing 10, generally in the shape of an inverted dome, is shown as formed with a stepped base 11, its flat annular base flange 12, having a beaded edge 13, containing openings 14 for the reception of securing means whereby the device is fastened in its 45 destined position.

The lower, conical end of the casing terminates in a cylindrical extension 15 and at several points in the cone, adjacent the junction, are prongs or lugs 16 formed by shearing the material, these prongs being bent radially inward to form supports for an insulating disc 17 containing openings 18 and

19 through which may be passed insulated wires leading from an electric supply source, downward through the casing to the socket 55 and plug carried by it, the lugs 16 also serve as stops against which the socket shell 25 abuts.

A row of perforations 20 are formed through the wall of the cylinder, the openings being uniformly, closely spaced and having flat bottoms 20'.

Surrounding the lower portion of the cylinder and completely covering the openings therein, is a ring or band 21 having an in-turned bottom edge 22, and in order to positively confine the band to the cylinder, a prong 23 is sheared from the band at one point, the same being passed through one of the openings 20 and then bent to lock 70 and firmly hold the parts together.

The socket or adapter, generally designated by the numeral 25, is identical in all respects with those of standard type except that the upper shell or casing may be slotted 75 at one or more points and is tight fitted to enter the element 15, no cap or cover being used as the socket body is fitted to engage directly in the canopy.

Formed to extend outwardly from the 80 socket are a plurality of rounded lugs 27, having relatively flat sharp bottoms 27' and suited to engage in the openings 20, being maintained therein by the resilience of the material, it is however possible to turn the 85 socket within the canopy and it will be obvious that relative adjustments can be readily be made.

It is further apparent that if the lugs 27 be positioned between adjacent openings 90 20, the socket may be withdrawn, the shell yielding upon the application of lateral pressure, and it will be equally clear that when the lugs 27 engage in the openings 20, withdrawal by force directed longitudinally cannot take place except by actual disruption of the material.

Having described my invention in such manner as to illustrate rather than restrict the same, what I claim as new and desire to 100 secure by Letters Patent, is:—

As an article of manufacture, a canopy adapted for attachment to a ceiling or wall and having an integral cylindrical extension

receptive of a standard electric socket shell, a plurality of lugs extending radially inward from the canopy adjacent its junction with the extension, against which the socket shell abuts, a band surrounding said extension, means for securing said band, a flange on said band abutting the end of said

extension, and means for releasably connecting the cylindrical extension directly with the socket shell.

Signed at New York in the county of New York and State of New York, this 4th day of January, A. D. 1922.

MITCHELL J. LUBOW.
